UNITED STATES PATENT OFFICE.

ARDEN C. PAGE, OF CINCINNATI, OHIO, ASSIGNOR TO THE LUCKY STAR MANUFACTURING COMPANY, OF CINCINNATI, OHIO, A FIRM CONSISTING OF ARDEN C. PAGE AND MITCHELL J. MILLER.

DESIGN FOR AN INCENSE-LOZENGE.

59,565.

Specification for Design.

Patented Nov. 1, 1921.

Application filed March 29, 1921. Serial No. 456,638. Term of patent 14 years.

To all whom it may concern:

Be it known that I, ARDEN C. PAGE, a citizen of the United States, residing at Cincinnati, in the county of Hamilton and State of Ohio, have invented a new, original, and ornamental Design for an Incense-Lozenge, of which the following is a specification, reference being had to the accompanying drawings, forming a part thereof.

The figure is a perspective view of the incense lozenge, showing my new design.

I claim:

The ornamental design for an incense lozenge, as shown.

ARDEN C. PAGE.
